[57] **ABSTRACT**

A module having open-bottomed containers from which liquid is displaced by gas for lifting submerged material. The containers are held in an inclined position so that excess gas can escape gradually, and mounted relative to each other so that no net moments are imposed on the module.

SELF-STABILIZING FLOTATION MODULE

BACKGROUND OF THE INVENTION

This invention relates to a flotation module for lifting submerged equipment or minerals.

As heavier loads at greater depths are desired to be lifted, the utility of pressure vessels decreases because of the increasing weight penalties. Although light weight flotation modules using the displacement of water by a gas have been employed, their usefulness has been impeded because of a lack of stability resulting in sudden drops in buoyancy.

SUMMARY OF THE INVENTION

In a preferred form of the invention, three or more open-bottomed containers are secured together in a module with their longitudinal axes upwardly inclined toward the vertical axis of the module. The containers are arranged so that any moment due to buoyancy is counterbalanced. The inclined attitude of the containers has two beneficial results: any excess gas will escape gradually from the uppermost portion of the container bottom instead of from an arbitrary location as would occur with a nominally vertical container; and if one container is more buoyant than the others it will rise and spill gas until the buoyancies are equalized resulting in a self stabilizing module.

BRIEF DESCRIPTION OF THE DRAWINGS

FIG. 1 is a schematic isometric of a flotation module in accordance with the invention;

FIG. 2 is a schematic cross section of one container of the module of FIG. 1; and

FIG. 3 is a schematic cross section of a gas generating device carried by a container.

DESCRIPTION OF THE PREFERRED EMBODIMENT

Referring to FIG. 1, a flotation module employing four open-bottomed containers is illustrated. The containers 10-16 may be of a thin wall construction since they are not intended to experience differential pressures. Each container has a reinforcing ring 18 at its bottom edge secured to a bottom brace 20.

A gas introducing or generating device 22 is provided so that a gas may be introduced into the containers when desired. Gas venting valve 23 permits easy submergence of the module by releasing gas. When the module is submerged and the containers are filled with gas, the resulting buoyancy will produce an upward force on the top of each of the containers which is transmitted to top braces 24 through top reinforcing structure 26.

As is more clearly shown in FIG. 2, the upward inclination of the longitudinal axis of container 14 (typical of each of the containers) results in a residual amount of water at the bottom of the container which is not displaced by incoming gas. It should be observed that if the inclination of container 14 were increased, gas would escape in the vicinity of region 26. Such an increased inclination would occur if container 14 contained a greater volume of gas than container 10, thereby having greater buoyancy. As gas escapes from container 14, however, its buoyancy is reduced until the total module achieves a stabilized attitude.

Because of the built-in inclination of containers 10-16, gas

will escape (whether due to an excess of gas or an increase in inclination) in a gradual rather than an abrupt manner. This reduces the tendency of the module to oscillate—releasing gas first from one side and then the opposite.

Various means may be utilized for introducing gas into containers 10-16. For example, hoses can be connected to valve 28 and to a source of compressed gas. At depths where a hose arrangement becomes cumbersome, however, a gas generator carried on the container can be employed. In FIG. 3, a gas generator 22 is illustrated which is secured in the top of each container.

A cylindrical pressure vessel 30 is provided to act as both the container for a solid propellant grain 32 and the combustion chamber in which this propellant will be burned. Propellant grain 32 may be of any suitable solid propellant material such as ammonium nitrate. An igniter 34 may be positioned at one end of vessel 30 and may comprise a squib of explosive material 36 containing a bridge wire 38 which will cause the squib to be ignited when a sufficient current passes through it. Current is supplied to bridge wire 38 by electrical cable 39. Igniter 34 also serves to close one end of pressure vessel 30 so that all gas which is generated within this vessel will be discharged at the opposite end. Closure 40 on the lower end of pressure vessel 30 incorporates gas discharge conduit 42 and one-way valve 44. One-way valve 44 comprises a ball 46 which serves to prevent liquid from entering vessel 30 through conduit 42 by closing orifice 48 under the biasing effect of spring 50 and the pressure of any liquid within conduit 42. Generation of gas within pressure vessel 30 dislodges ball 46 and permits the gas to be discharged through conduit 42 and into the container.

In operation, the self stabilizing flotation module of this invention may be placed in the water and submerged by venting entrapped gas. At the desired location, it may be attached to an object, and the water within the containers displaced by gas.

While a particular embodiment of a self stabilizing flotation module has been shown and described, it will be evident that changes and modifications can be made without departing from the spirit of the invention and the scope of the appended claims.

I claim:

1. A self stabilizing flotation module for providing thrust in a liquid environment comprising:
at least three open-bottomed containers;
means connecting said containers to each other and maintaining them in a fixed position relative to each other; the longitudinal axis of each of said containers being upwardly inclined toward the vertical axis of said module; said containers being so sized and arranged that when filled with gas the sum of the moments of force on said module is zero; and
means for introducing a gas into said containers for displacing liquid therefrom.

2. A self stabilizing flotation module in accordance with claim 1 wherein:
said means for introducing a gas into said containers is a gas generating device secured to the container.
3. A self stabilizing flotation module in accordance with claim 2 wherein:
said gas generating device includes a solid propellant grain of ammonium nitrate.
